(57) **CLAIM**

The ornamental design for wearable key fob cuff band, as shown and described.

DESCRIPTION

FIG. 1 is a perspective view illustrating a embodiment of a wearable key fob clip of the claimed design;

FIG. 2 is an front view of the wearable key fob clip shown in FIG. 1;

FIG. 3 is a back view of the wearable key fob clip shown in FIG. 1;

FIG. 4 is a right view of the wearable key fob clip shown in FIG. 1;

FIG. 5 is a left view of the wearable key fob clip shown in FIG. 1;

FIG. 6 is a top view of the wearable key fob clip shown in FIG. 1; and,

FIG. 7 is a bottom view of the wearable key fob clip shown in FIG. 1.

1 Claim, 5 Drawing Sheets
